UNITED STATES PATENT OFFICE.

CARRIE M. CAVALINE, OF PORTLAND, OREGON, ASSIGNOR OF FORTY ONE-HUNDREDTHS
TO FRED B. MORGAN, OF PORTLAND, OREGON.

FOLDABLE TABLE.

1,204,648.

Specification of Letters Patent. Patented Nov. 14, 1916.

Application filed January 13, 1915. Serial No. 2,080.

To all whom it may concern:

Be it known that I, CARRIE M. CAVALINE, a resident of the United States, and a resident of Portland, county of Multnomah, 5 State of Oregon, have invented a new and useful Improvement in Foldable Tables, of which the following is a specification.

My invention has for its object the providing of a foldable table, which may be 10 folded into compact form so as to adapt the same for being conveniently carried about. To this end my table comprises a top, consisting of a plurality of detachable leaves, and the top is supported at each end by a 15 trestle-like support, each support consisting of a top-rail mounted at each end on a pair of scissor-jointed legs, which may be fastened to said top-rail when the table is set up, and being adapted to be otherwise 20 folded lengthwise with the top-rail; a pivoted strut connects one of each pair of legs to the top rail, and a brace bar, pivoted to one of the companion legs, is adapted for locking the latter in extended position.

25 Other details of construction and features of my foldable table are hereinafter more fully set forth:

In the accompanying drawings, Figure 1 is a side elevation of my table as it appears 30 when set up; Fig. 2 is a top view of the table-top showing the latter as consisting of four leaves which are connected at their abutting edges by suitable locking means. Fig. 3 is a transverse section on line 3—3 of 35 Fig. 2. Fig. 4 is a view of the end side abutting portions of two adjacent leaves of the table-top, and particularly a means for locking one with the other so as to maintain the table-top in level position as a whole. Fig. 5 is a section taken vertical of Fig. 4. 40 Fig. 6 is a sectional detail showing the tops of one pair of scissor-jointed legs, the top rail with which the tops of said legs are locked, the channel bar which is placed on 45 the top-rail; and this view also shows the leaves of the table-top as resting on the trestle-supports. Fig. 7 is a bottom view of said channel bar. Fig. 8 is a top view showing a detail of construction relating 50 to the interlocking of the top rail, the upper ends of the scissor-jointed legs, and the channel bar, the latter being shown in dotted outline. Fig. 9 is a perspective view of one of the trestle-supports of my table, showing 55 one pair of collapsible scissor-jointed legs

as arranged in supporting position and in the right hand portion of this figure is illustrated the process of setting up and collapsing said legs; and Fig. 10 is a perspective sectional detail of the top rail of one 60 of the trestle supports of my table, in connection with the channel bar which is placed on the top rail.

The top *a*, of my table is made of a plurality of leaves, *a'*, detachably connected 65 by suitable means at their abutting edges. The means which I find convenient to use comprise a latch-plate, *b*, and a latch-bar, *c*, the latter being made at its extremity with a bent over, or claw portion, *c'*.

In assembling the leaves, preferably the center leaves are first placed in abutment and locked together against lateral movement from each other. Such locking together is readily accomplished by simply 70 resting the inner edges of the two middle leaves on the trestle support placing such inner edges in abutment, meanwhile holding the outer edges of such leaves slightly elevated, then dropping the outer edges of the 75 leaves on the trestle support, the latch-bars, *c*, will thus be engaged with the latch-plates, *b*.

The table top is supported at its ends by two trestle-like supports of which one is 80 perspective shown in Fig. 9. Each support consists of a top rail, *d*, provided at its ends with recessed portions, *e*. At each end of the rail, *d*, are provided a pair of scissor-jointed supporting legs, consisting of 85 members, *f*, *g*, connected by a pivot, *h*. The upper ends of the legs, *f*, *g*, are recessed as at *i*, so as to provide supporting shoulders, and said recessed upper portions are inserted in the recesses, *e*, of the rail, *d*, as 90 illustrated in Fig. 6. One of the legs, *f* for example, is tied to the rail, *d*, by a pivoting strut, *j*, and to the leg *f* is furthermore pivoted a brace-bar, *k*, the free end of which is adapted to be fastened to a stud-pin, *l*. When the legs of the supporting trestle are set up, the latter will appear as 95 shown in Figs. 1, 3 and 9. It will be noted that as soon as the legs have been set up in their proper position and the brace-bar, *k*, is fastened at its free end to the stud-pin, *l*, the legs are firmly held in their set-up state. When the table is to be carried about, the brace-bar, *k*, is first unlatched and the 100 legs may then be folded together in com-

110

pact form so as to reduce the supporting trestles into a small bulk. It will be noted from Fig. 1, that the supporting trestles are arranged transversely under the table top. 5 In order to stiffen the supporting trestles and provide a wider supporting surface than that afforded by the top rails, *d*, I prefer to place on the latter a channel bar, *m*, which is fastened on the top-rail *d*, by 10 means of a hook and stud, *n'*. The channel bar, *m*, is provided with recesses, *o*, at its sides, corresponding to the recesses, *e*, of the top-rail, *d*, and like the latter, being adapted to receive the tops of the trestle 15 legs, *f*, *g*. By reason of this construction, the top-rail, *d*, need not be made of a length equal to the width of the top, but can be made of any convenient length, since the channel-bar, *m*, serves to support the outer- 20 most leaves of the table-top. The channel-bar, *m*, is provided at its extremities with hooks, *p*, adapted to hold the sides of the table top against moving over the ends of the channel-bar, *m*; see Figs. 3 and 7.

25 I claim:

1. In a foldable table, the combination of a foldable trestle comprising a top-rail and a pair of scissor-jointed legs at each end of the top-rail, a channel bar adapted to be removably placed on said top-rail, the sides of said channel bar being provided with recesses adapted to receive the upper ends of said scissor-jointed legs, and means for fastening said channel bar on the top-rail. 30
2. In a foldable table, the combination of a foldable trestle comprising a top-rail and a pair of scissor-jointed legs at each end of the top-rail, said top-rail being provided with recesses for receiving the upper 35 ends of said legs, a channel-bar adapted to be removably placed on said top-rail, having

its sides cut away in correspondence with said recesses of the top-rail, and means for fastening the channel bar on the top-rail.

3. In a foldable table, in combination 45 with a removable table top, trestle supports for the ends of the latter, each consisting of a top-rail, a pair of scissor-jointed legs for each end of the top-rail, means for removably connecting the upper ends of 50 said scissor-jointed legs to said top-rail, a strut jointedly connected at one end to the top-rail and at the other to one of said pair of legs, means for securing said pair of legs in spread-apart position, 55 a channel bar having its sides cut away in correspondence with said recesses of the top-rail, means for fastening the channel-bar on the top-rail, and means for restraining the table-top against lateral movement on 60 the channel bar when resting on the latter.

4. In a foldable table, in combination with a removable table-top, trestle supports for the ends of the latter, each consisting of a top-rail, a pair of scissor-jointed legs for 65 each end of the top-rail, the top-rails being provided with recesses for receiving the upper ends of the legs, a strut jointedly connected at one end to the top-rail and at the other to one of said pair of legs, means for 70 securing said pair of legs in spread-apart position, a channel-bar having its sides cut away in correspondence with said recesses of the top-rail, means for fastening the channel-bar on the top-rail, and means for restraining the table top against lateral movement on the channel-bar when resting 75 on the latter.

CARRIE M. CAVALINE.
